CLAIM

The ornamental design for a vehicle front bumper, as shown and described.

DESCRIPTION

FIG. 1 is a front and left side perspective view of a vehicle front bumper showing our new design;

FIG. 2 is a front elevation view thereof;

FIG. 3 is a left side elevation view thereof, the right side being a mirror image of the left side shown; and,

FIG. 4 is a top view thereof.

The broken lines shown in the Drawings depict portions of the vehicle front bumper that form no part of the claimed design.
